(57) **CLAIM**

The ornamental design for top of a cage for small pets, as shown and described.

DESCRIPTION

The characteristic feature of the design resides in the accessible compartment formed within the cage top.

FIG. 1 is a perspective view of a top of a cage for small pets;

FIG. 2 is a top view thereof;

FIG. 3 is a left side view thereof;

FIG. 4 is a right side view thereof;

FIG. 5 is a front view thereof;

FIG. 6 is another perspective view thereof showing the access door in opened position;

FIG. 7 is another left side view thereof in opened position; and,

FIG. 8 is a rear view thereof in opened position.
